TELEPHONE PAY STATION TARIFF
INDICATOR

Heinrich Langner, Berlin-Steglitz, Germany, assignor to Telephon-Apparat Fabrik E. Zwiebusch and Company, Berlin, Germany

Application January 4, 1936, Serial No. 57,501
In Germany January 23, 1935

4 Claims. (Cl. 179—6.3)

This invention relates in general to indicators but more particularly to indicators such as are used at telephone paystations for indicating to a subscriber whether the day or the night time rates for calls are in effect at the time he is about to make a call.

For paystations it has already been proposed to supervise the operating condition of the line as to whether it is free or engaged and which tariff (day or night) is in effect, by means of a polarized relay. The relay has one winding connected to one conductor of the line and one winding connected to the other conductor of the line and is correspondingly energized by battery potential at the exchange according to the time of day, over the one conductor, the other conductor or over both. The member with which the relay is provided for the purpose of acting as an indicator is accordingly moved to one or other of the positions on a suitable scale.

The invention is directed to the perfection of a device of this type and at the same time make it more simple in construction. The indication of day or night tariff and of the operating condition of a pay station is effected according to the invention by means of a galvanometer which is fed from battery at the exchange over only one lead or conductor of the line, and whose single winding is energized more strongly or less strongly over the windings of a relay of which one of the windings may be short-circuited. In order to make the armature draw up more satisfactorily thus enabling a finer adjustment of the indicator a spring is arranged in the path of the armature or indicator. The indicator for example presses lightly against this spring in the first energizing stage while on the second energizing stage the pressure of the spring has to be overcome by the stronger current flow produced.

On removing the hand set from the switchhook a spring controlled by the former is pressed into one of the notches provided in the armature, so that the indicator still remains in the position which it has taken up when the current is disconnected on removing the hand set from the switchhook. According to the invention the tariff indicator produced is of considerable sensitivity and yet stays firm in any of the indicating positions in spite of considerable current variations, being held in position until the end of the call.

One embodiment of the tariff indicator according to the invention is represented in the drawing.

Fig. 1 represents an elevation of the tariff indicator partly cut away.

Fig. 2 represents a plan view of the tariff indicator shown in Fig. 1.

Fig. 3 gives a diagrammatic representation of the circuit arrangement.

The galvanometer 2 which is supported on a mounting plate 1, consists essentially of a winding 3 and an armature 4 which carries an indicator 5. The piece 6 bent out from armature 4 is provided with notches 7 for receiving the holding spring 8. The holding spring 8 is fixed to one end of the lever 10 which is rotatably mounted on the pivot 9 while at the other end of this lever is arranged the bar 11 which is controlled by the switchhook. This arrangement is to hold the indicator in its set position for the duration of a call while the receiver is off the switchhook. The spring 8 is removed from the notches 7 when the receiver is replaced. The spring 13 which is fixed to the galvanometer 2 or to the container 12 opposes the motion of the indicator 5. It is so tensioned that the indicator 5 only presses lightly against its projection 14 when indicating the day tariff; the indicator then being visible through the window 15 in the container panel 16 for example in the middle of the scale 17. The winding 3 of the galvanometer (Fig. 3) is connected, for example, by way of the line conductor with a resistance 18 of the exchange. The resistance 18 (which may be included in any of the relays of the line, such as a control relay) has two windings 19 and 20 one of which is short circuited by contact 21 when the night tariff is in effect, thereby causing an increase in the current strength. In this case the circuit extends from: earth, battery, operated contact 21, winding 19 of resistance 18, winding 3 of the galvanometer to earth.

The armature 4 is accordingly drawn up into the winding 3 against the force exerted by the spring 13 so that the indicator 5 in the window 15 moves to that part of the scale 17 indicating night tariff. Should the line to the pay station be cut off for any reason the indicator 5 drops to the lowest position of the scale 17 on account of winding 3 becoming deenergized, and in this position indicates that the station is out of order.

What is claimed is:

1. In a paystation tariff indicator, a galvanometer having an indicator arm for indicating the tariff at the paystation, said galvanometer connected in the paystation line circuit, means responsive to the initiation of a call for transmitting a weak current over said line circuit to

50 55

operate said galvanometer to move its indicator to a middle position indicating the day rate, or for transmitting a strong current over the line to operate the galvanometer to move its indicator to the furthest position to indicate the night rate, and means in the pay station for holding the indicator in any set position only as long as the switchhook thereat is operated.

2. In a paystation tariff indicator, a galvanometer having an indicator arm for indicating the tariff in effect at the paystation, said galvanometer normally connected in the line circuit of said paystation, means for transmitting currents of various strengths over said line to operate the galvanometer to vary the position of its arm and thereby indicate at the paystation the tariff prevailing, means responsive to the initiation of a call from said paystation for holding said indicator arm in its set position, and means

responsive to the termination of the call for again releasing said indicator arm.

3. In a paystation tariff indicator as claimed in claim 2 in which the indicator arm is held in set position for the duration of a call under control of the switchhook of the paystation.

4. In a paystation tariff indicator, a galvanometer having an armature to which an indicator is attached, means for operating said galvanometer to move the indicating arm to any one of a plurality of positions to indicate certain rates for calls, said armature provided with a series of notches corresponding to the rates, a spring member, and means controlled by the paystation switchhook for moving said spring member into engagement with one of said notches to hold said indicator arm in its set position for the duration of the call.

HEINRICH LANGNER.
